UNITED STATES PATENT OFFICE.

DUANE F. ALLERTON, OF BENTON HARBOR, MICHIGAN.

DESIGN FOR A WRENCH.

SPECIFICATION forming part of Design No. 29,985, dated January 10, 1899.

Application filed October 6, 1898. Serial No. 692,871. Term of patent 14 years.

To all whom it may concern:

Be it known that I, DUANE F. ALLERTON, a citizen of the United States, residing at Benton Harbor, in the State of Michigan, have invented and produced a new and original Design for Wrenches, of which the following is a specification, reference being had to the accompanying drawings, forming a portion thereof.

In the drawings, Figure 1 is a view of the under side of my wrench, while Fig. 2 is a section on line 2 2 of Fig. 1.

Referring now to the drawings, the leading feature of my invention consists in the formation of the rectangular open head, having one side beveled downwardly to an edge, a portion being cut away from each side, grooves in a common line entering or opening into the cut-away portion.

In the drawings, 5 represents the open head,

to which a handle 6 is attached, one side 7 of the head being beveled downwardly to a sharp edge 8, the cut-away portion 9 being formed upwardly from the edge 8 in the form of an arch. Grooves 10 and 11 are formed in 25 a common line at either side of the cut-away portion 9 and opening thereinto, said grooves being on the outer face of the side 7. The opening of the head 5 is angular, as shown.

Having thus described my invention, what 30 I claim is—

The design for a wrench as herein shown and described.

In testimony whereof I affix my signature in presence of two witnesses.

DUANE F. ALLERTON.
